Primary Examiner — Katherine Glennon(74) *Attorney, Agent, or Firm* — Fross, Zelnick, Lehrman & Zissu, P.C.; Charles T. J. Weigell, Esq.(57) **CLAIM**

The ornamental design for a watch dial, as shown and described.

DESCRIPTION

FIG. 1 is a front elevational view of a watch dial showing my new design;

FIG. 2 is a back elevational view thereof;

FIG. 3 is a top plan view thereof;

FIG. 4 is a bottom plan view thereof;

FIG. 5 is a left side elevational thereof;

FIG. 6 is a right side elevational view thereof; and,

FIG. 7 is a front, right side perspective view thereof.
